AUXILIARY COUNTERBALANCE FOR
EXTRA CAPACITY HEAD

Edwin R. Goldfield, University Heights, Ohio, assignor to Waite & Bartlett X-Ray Mfg. Co., Inc., Cleveland, Ohio, a corporation of New York

Application August 27, 1935, Serial No. 38,075

2 Claims. (Cl. 248—123)

This invention relates to mobile X-ray apparatus having a tube head capable of maximum range of vertical adjustment thereon, the apparatus being intended to be movable from room to room of the hospital or other building in which it is to be used.

The principal object of the invention is to provide that the possible vertical adjustment of the parts may be maximum and greater than the height of the usual doorway, yet the apparatus be of small enough height to clear such doorway.

Another object of the invention is to make the apparatus capable of employment with a tube head selected from a number thereof according to capacity, type and the like, depending on the work to be performed—yet retaining the advantages described with respect to clearance.

Further objects and advantages of the invention will be apparent from the following description taken in connection with the drawing, in which

Fig. 1 is a side elevation of typical apparatus embodying the invention, the parts being shown as adjusted to an intermediate position, parts being broken away to show details of the construction, and the view illustrating in broken lines another adjusted position;

Fig. 2 is an enlarged plan view of certain parts appearing in Fig. 1;

Fig. 3 is a sectional detail in elevation as in the plane of line 3—3, Fig. 2; and

Fig. 4 is a detail of parts appearing in Fig. 3 as in the vertical plane of line 4—4, Fig. 3.

With reference now to the drawing, the principal parts of the apparatus include a mobile base 1 provided with wheels or the like as indicated, a hollow post 2 carried by the base 1 and extending upwardly therefrom, and a carriage 3 vertically adjustable along the post 2. An X-ray head 4 which may be of shock-proof type and including the usual X-ray tube and high tension transformer therefor, is detachably mounted on the carriage 3 and arranged for universal adjustment relative to the carriage as indicated, Fig. 1, and as will be appreciated by one familiar with the art. A control box 5 for the head 4 and connected with the latter as by cable 6, is mounted on the base 1.

Weight means for counterbalancing the carriage 3 and tube head 4 are provided and arranged to move within the hollow of the post 2 for the purpose. As here shown, the weight means includes a weight 7 connected with the carriage as by a flexible line 8, which runs over a sheave 9 mounted at the top of the post 2 and

overhanging the hollow of the post as indicated, the sheave being immediately carried by a suitable bracket 10 at the head of the post and so disposing the sheave that the stretch 8a of the line 8, suspending the weight 7 from the sheave 9, will be centrally disposed in the hollow of the post 2 while the stretch 8b of the line 8 suspends the carriage 3 from the sheave 9 will be disposed outside the post and clear thereof.

The bracket 10 is adjustable about the axis of 10 the post 2 and carries an end of a rod 10a, the lower end of which is carried by a collar 10b, similarly adjustable about the post axis. The carriage 3 has means such as a pair of rollers 3a moving on the rod 10a, the arrangement being 15 such that the carriage 3, together with the sheave 9, may be adjustable as a unit about the axis of the post.

The weight 7 may be cylindrical and substantially occupy the entire hollow of the post, in horizontal section, and the parts are so proportioned and arranged, and particularly, the line 8 is of such length, that the tube head 4 may have adjustment the full length of the post 2, yet when the head is in lowermost position the weight 7 will lie within the hollow of the tube 2 and below the sheave 9.

The weight means includes an auxiliary weight 7'. This auxiliary weight is detachably mounted upon the permanent weight 7 in indexed relation 30 with the latter as by pins 11. The weight 7' is generally cylindrical but has a longitudinally extending slot 12 whereby the auxiliary weight may clear the sheave 9 and stretch 8a of the line 8 and may thus extend substantially above the 35 post 2, when the head 4 is in lowermost position, as shown, Fig. 3, and in broken lines, Fig. 1. The auxiliary weight may also have a flat side as at 13 adjacent its slot 12 to clear parts of the bracket 10, as shown, Fig. 2.

The length of the post 2 is such that the apparatus may just clear the usual doorway when the parts are in intermediate positions, such as that shown in full lines, Fig. 1, whereas when the tube head is in lowermost position and the weight 45 means projects substantially above the post, as in Fig. 3, and in broken lines, Fig. 1, the auxiliary weight 7' would not pass through the doorway.

The relative masses of the weights 7 and 7' are such that when the auxiliary weight 7' is removed, the permanent weight 7 will be sufficient to counterbalance a lighter tube head which may be substituted on the carriage 3 for the tube head 4 shown thereon. Thus, when such lighter tube head is to be used, the auxiliary weight 7' is re- 50 55

moved. This is easily accomplished simply by lowering the carriage 3 sufficiently to project the auxiliary weight 7' above the post 2, and then lifting the auxiliary weight 7' from the weight 7 and 5 removing it from the apparatus.

What I claim is:

1. In mobile X-ray apparatus of the class described, and having upright post means and a carriage adjustable therealong, a head mounted 10 on said carriage, weight means sufficient to counterbalance said carriage and head, sheave means at the upper end of said post means, and a line interconnecting said weight means and carriage and passing over said sheave means, said weight means having a longitudinally extending 15 opening to clear said sheave, and the parts being so proportioned and arranged that when said carriage is in lowermost position said weight means will project substantially above said post means, but said carriage may be adjusted to an intermediate position wherein neither said carriage nor said weight means will project above 20 said post means.

2. In mobile X-ray apparatus of the class de-

scribed and having upright post means and a carriage adjustable therealong, a head mounted on said carriage, sheave means at the upper end of said post means, and weight means for counterbalancing said carriage and head and 5 comprising a permanent weight, a line interconnecting said permanent weight and carriage and passing over said sheave means, the parts being so proportioned and arranged that when said carriage is in lowermost position and said permanent weight in corresponding uppermost position, said permanent weight will be at a lower 10 elevation than said sheave means but adjacent the latter, said permanent weight having a part overhung by said sheave means, said weight 15 means including an auxiliary weight detachably mounted upon said permanent weight to extend above the sheave elevation when said permanent weight is in its said uppermost position and having a longitudinally extending opening to clear 20 said sheave means and line when said permanent weight is lowered from its said uppermost position.

EDWIN R. GOLDFIELD.
